ATTORNEY.

UNITED STATES PATENT OFFICE.

ARTHUR HUGHES, OF LOS ANGELES, CALIFORNIA.

PUTTEE TRIMMER.

Application filed June 2, 1921. Serial No. 474,485.

To all whom it may concern:

Be it known that I, ARTHUR HUGHES, a citizen of the United States, residing at Los Angeles, in the county of Los Angeles and State of California, have invented new and useful Improvements in Puttee Trimmers, of which the following is a specification.

This invention is a puttee trimmer including a support for a puttee and a mechanism laterally shiftable relative to the puttee and its support and carrying rotary cutters for trimming off the ends of a puttee, and also having longitudinally extending spaced blades adapted to engage the puttee after the end cutters have functioned for slitting the puttee at opposite sides of the seam formed therein. By this arrangement the trimming of the puttee is accomplished by a single operation.

The invention will be readily understood from the following description of the accompanying drawings, in which:

Figure 1 is a side elevation of the device constructed in accordance with the invention.

Fig. 2 is a transverse section on the line 2—2 of Fig. 1.

Figs. 3 and 4 are detail sections on the lines 3—3 and 4—4 of Fig. 1.

Fig. 5 is a detail section on the line 5—5 of Fig. 2.

The machine preferably includes a suitable table 1 having a guide bar 2 upon the same and also provided with brackets 3 extending upwardly from the respective ends of the table and connected by a guide bar 4.

The work supporting means comprises a grasping device formed of scissor arms 6 pivoted in a bracket 7 beneath table 1 so that said arms extend upwardly in order to hold a puttee support and the puttee mounted thereon. Two pairs of arms 6 are preferably employed and are longitudinally spaced in order to form the necessary support for the puttee holder.

The operating ends of the arms beyond their pivotal connection 9 extend below table 1 and are connected by bars 10 which are in turn connected to operating straps 11 leading to a foot treadle 12. This treadle is pivoted at 12 as shown at 13, and the opposite end of the same is provided with a laterally projecting locking lip 14 adapted to engage a notched rack 15 for holding

the treadle in various positions so as to firmly clamp the scissor arms 6 upon the work support.

The work support is a member 16 upon which a puttee 17 is mounted, and said support and puttee are held within scissor arms 6 so that the seam 18 in the puttee is turned upwardly.

The cutting mechanism includes bearings 20 slidable upon guide bar 4 and adapted to be locked in position by means of set screws 21. Supporting rods 22 are pivotally connected to bearings 20 and are adapted to be locked in angularly adjusted positions by means of set screws 23. The lower ends of the supporting rods 22 are connected to grooved members 24 which are slidably mounted upon guide bar 2. The supporting rods 22 are positioned beyond the respective ends of the work support and the puttee mounted thereon, and it will be noted that the construction as described permits of longitudinal adjustment of said supporting rods relative to the puttee, and also provides for slight angular adjustment of said supporting rods.

Frames 26 are slidably mounted upon rods 22 and may be locked to said rods by means of set screws 27. These frames carry driving mechanisms shown as electric motors 28 having the shafts 29 of said motors extending through the frames 26 with rotary cutters 30 fixed upon the ends of said shafts and facing one another adjacent the respective ends of the puttee mounted upon the work support.

Longitudinally extending blades 32 which are transversely spaced from one another are supported at their respective ends by the frames 26 so that said blades extend the length of the puttee upon the work holder, and said blades are mounted above the rotary cutters, 30, so that the latter may first operatively engage a puttee and then permit subsequent slipping of the puttee by means of said longitudinal blades.

As an instance of this arrangement, bracket arms 33 extend upwardly from frames 26, and screw rods 34 connect said bracket arms with nuts 35 threaded upon right and left hand threads 36—37 formed at the respective ends of the screw rods engaging the respective blades.

At one end of the machine the nuts 35 may be fixed in openings extending through

the blades, while at the opposite end of the machine the nuts are slideable in slots 40 provided in said blades. The screw rods are provided with slideable operating heads 41 so that rotation of the same will adjust the blades toward and away from one another. It will also be noted that the provision of slots 40 in the longitudinal blades permits of longitudinal adjustment of supporting rods 22 and the frames 26, while still maintaining the longitudinal blades in operative position.

Handles 45 extend from bracket arms 33, and in operation the handles are grasped so that frames 26 may be elevated upon supporting rods 22. The cutting mechanism is locked in this elevated position by means of set screws 27, and a puttee to be trimmed is then mounted upon the work holder and supported in the scissor arms 6. The supporting rods 22 having been properly adjusted, the frames 26 are released and the cutting mechanism is then moved downwardly to cause the rotary cutters 30 to trim off the ends of the puttee. It will be noted that this cut may be made at the desired angle by angularly adjusting rods 22.

When cutters 30 have completed their work, the longitudinal blades 32 will engage the puttee at the respective sides of seam 18 in order that a subsequent depression of the cutting mechanism will slit the puttee. The cutting mechanism may then be again elevated and the trimmed puttee removed from the work holder.

Various changes may be made without departing from the spirit of the invention as claimed.

What is claimed is:

1. A trimmer including a longitudinal work support, a longitudinal guide, supports extending laterally from said guide and longitudinally and angularly adjustable thereon, frames slideable upon said supports, longitudinal blades adjustably connected to said frames, and rotary cutters carried by said frames and laterally spaced from said longitudinal blades toward said work support.

2. A trimmer comprising an article holder, jaws adapted to clamp an article upon said holder and support the same, cutting mechanism shiftable laterally relative to said article holder and including longitudinal blades, and rotary cutters laterally spaced from said longitudinal blades and toward said article holder.

3. A trimmer for puttees comprising a work support, cross arms for securing the work in snug relation to the support, rotary cutters at the ends of the support, means for vertically and horizontally adjusting the cutters, blades above the support and movable toward and away from the latter, and manually operable means for actuating the blades.

4. A trimmer for puttees comprising a work support, means for clamping the work to the support, rotary cutters for engagement with the end portions of the work, a pair of blades above the support and movable toward and away from the latter, and means for adjusting the relative positions of the blades with respect to each other.

In testimony whereof I have signed my name to this specification.

ARTHUR HUGHES.
